UNITED STATES PATENT OFFICE

2,155,330

HEALTH PROTECTION MEMBER

Martha Pottenger, Chicago, Ill.

Application February 16, 1938, Serial No. 190,811

1 Claim. (Cl. 135—5)

My invention relates to an inclosure adapted to protect the user therein against insects and dampness.

Among the objects of my invention are to provide a device in which a user or users may sleep or eat with unlimited fresh air, sunshine and coolness and yet which will protect against discomfort from insects, snakes, grasshoppers and the like and against dampness; to provide means in which a cot, bedding or picnic table and chairs may be positioned and the users therein protected; to create a device light enough to be portable and yet sufficiently strong in construction to be lasting in use; to supply a member having means for easy entry and exit of the user, and means for forming a perfect closure and such other objects, advantages and capabilities as will later more fully appear which are inherently possessed by my invention.

Referring to the drawing Fig. 1 is a perspective view of one embodiment of my health protection member for sleeping; Fig. 2 is a longitudinal sectional view of the head portion of the embodiment shown in Fig. 1; and Fig. 3 is a perspective view of another embodiment of my invention, particularly for use over picnic tables.

While I have shown preferred embodiments herein of my invention, yet I wish it understood that the same are susceptible of modification and change without departing from the spirit of my invention.

Referring to one embodiment selected to illustrate my invention it comprises a flat floor or bottom member 10 of preferably heavy water-proof material such as canvas or the like. Sewed or otherwise permanently attached to each of the edges of the floor member 10 are abbreviated side portions 11, abbreviated foot portion 12 and a larger head portion 13, all of the same kind of material as the floor member 10. Sewed or otherwise permanently attached to each of the upper edges of the side portions 11 are side portions 14 of heavy mosquito-proof netting. Also sewed or otherwise permanently attached to the upper edges of the foot portion 12 and head portion 13 are foot and head portions 15 and 16 respectively of heavy mosquito-proof netting.

A flat top member 17 of heavy mosquito-proof material has its outer edge sewed or otherwise permanently attached to the upper edge of the side portion 14 and the foot and head portions 15 and 16.

A substantially narrow reinforcing strip 18 of heavy material such as canvas permanently attached by sewing on the like to each of the outer

edges of the top member 17 as they meet and are attached to the upper edges of the side portions 14 and the foot and head portions 15 and 16.

A substantially narrow reinforcing strip 19 is permanently attached by sewing on the like to each of the corners 20 and extend upwardly and are bent over and are permanently attached to the top member 17.

The inner ends of ties 20 are attached to each of the strips 19 preferably at their top and bottom portions to be attached to a pole 21 adapted to be driven into the ground or otherwise held at the base and having notches 22 to prevent slipping of the ties 20.

Beginning at the foot portion 12 and continuing around into one of the side portions 11 I provide an opening 23 and a slide fastener 24 for closing the same. The position and extent of my opening 23 and slide fastener 24 may be varied without departing from the spirit of my invention so long as the user may be able to enter my health protection member with reasonable ease and upon entry may close himself completely therein by the mere operation of the slide fastener.

Another embodiment of my invention more particularly shown in Fig. 2 provides a health protecting means in the shape of a room adapted to be used for picnic purposes so that the table, chairs and picnickers may be within the member and protected from mosquitoes, flies and other nuisances. My structure is the same as the embodiment shown in Fig. 1 with the addition of a three sides opening 25 in the bottom member 10 with a slide fastener 24 adapted when opened to form a flap 26 so as to enable the entire member to be placed over the picnic table. The slide fastener could then be closed to form a closed bottom 10. Another difference between this embodiment and my other embodiment is that instead of a horizontal opening 23 in side portion 11 I provide a vertical opening in one of the reinforcing strips 19 with a slide fastener 24 for entry and withdrawal.

With my embodiment shown in Fig. 1, I may make it large enough for one or more persons and also of sufficient size so that a cot, bed or bedding may be placed therein. Upon the user or users entering my health protection member through the opening the slide fastener may then be operated to close the opening and completely shut the user or users therein. Complete protection is then assured with perfect comfort.

Having thus described my invention I claim:

A device of the character described comprising a bottom member of heavy water-proof material, abbreviated side, foot and head portions of water-proof material attached to outer edges of said bottom member, side, foot and head portions of mosquito-proof netting attached at their lower edges to the upper edges of the abbreviated side, foot and head portions, a top member of heavy mosquito-proof netting attached at its outer edges to the upper edges of the side, foot and head portions of the mosquito-proof netting of the water-proof material, a plurality of said abbreviated side, foot and head portions having a continuous opening, and a slide fastener for closing said opening, a plurality of substantially nar-

row horizontal strips attached to the top member adjacent its outer edges and to the side, foot and head portions of the mosquito-proof netting adjacent their upper edges for reinforcing the attachment of said top member and said side, foot and head portions, a plurality of substantially narrow vertical strips attached to the side edges of said side, foot and head portions, the upper ends of said strips attached to said top member, straps attached to each of said vertical strips adjacent their upper and lower ends, and notched poles positioned in the ground, said straps adapted to be tied to said poles.

MARHTA POTTEGNER. 15
